UNITED STATES PATENT OFFICE.

FRANK H. KINSMAN, OF NEVADA, IOWA.

LEADING RACK.

1,403,789.

Specification of Letters Patent. Patented Jan. 17, 1922.

Application filed January 28, 1921, Serial No. 440,750. Renewed November 26, 1921. Serial No. 518,069.

To all whom it may concern:

Be it known that I, FRANK H. KINSMAN, citizen of the United States, residing at Nevada, in the county of Story and State of Iowa, have invented certain new and useful Improvements in Leading Racks, of which the following is a specification.

My invention relates to a leading device or rack, adapted to be secured to the rear of 10 a wagon, body, or the like, and to have the horse or horses of the rear wagon, connected therewith.

An important object of the invention is to provide a device of the above mentioned 15 character, adapted to prevent the horse or horses of the rear wagon, from moving forwardly too close to the front wagon, whereby the end gate or the like of the front wagon may be broken, by the pole or the like of the 20 rear wagon.

A further object of the invention is to provide a device of the above mentioned character adapted to be securely held in the opened or active position, to be swung to an upper 25 position to permit of the discharge of the material from the rear end of the wagon body at an elevator or the like, and to be swung to a lower position, out of the way, and held in such lower position, when not 30 in use.

A further object of the invention is to provide a device of the above mentioned character which is simple in construction and inexpensive to manufacture, convenient in use, 35 and may be installed upon the ordinary wagon body without materially altering the construction thereof.

Other objects and advantages of the invention will be apparent during the course 40 of the following description.

In the accompanying drawings forming a part of this specification, and in which like numerals are employed to designate like parts throughout the same,

45 Figure 1 is a perspective view of a device embodying my invention, showing it in the active or horizontal position;

Figure 2 is a similar view showing the rack raised, to permit of the discharge of 50 material from the rear end of the wagon body;

Figure 3 is a similar view with the rack held in the lower position;

Figure 4 is a detail vertical section through 55 a holding bracket, and

Figure 5 is a fragmentary perspective

view of the elements of the rack, separated, and in a position to be assembled.

In the drawings, wherein for the purpose of illustration, is shown a preferred embodiment of my invention, the numeral 10 designates a wagon body, of any well known or preferred type, having an end gate 11.

My device or leading rack embodies a preferably U-shaped frame 12, which may be 65 preferably formed of a metal rod, bent into the desired shape. Each end of this U-shaped frame 12 is bent into a hook 13, inserted in an eye 14, for pivotal movement therein, this eye being secured to the body of the wagon, 70 at its rear end. It is thus seen that the frame 12 is adapted to be swung in a vertical plane in relation to the body of the wagon. The frame is preferably reinforced or stiffened by diagonal rods 15, connected therewith, as 75 shown.

The numeral 16 designates eyes or loops, preferably secured to the frame 12, near or at its corners, and these eyes may be employed to receive the lines, or the like, for 80 hitching the horse or horses, of the rear team, to the frame 12, while of course the invention is in no sense restricted to this idea, as other suitable forms of connecting means may be employed.

The numeral 16' designates diagonal supporting or locking rods, each of which, Figure 5, is provided at its outer end with an eye 17, to receive a pivot element or bolt 18, and passing through an aperture 19, in a 85 flattened portion 20 of the frame 12, which flattened portion is arranged near the outer end of the frame. Each supporting rod 16' is adapted for insertion through a preferably vertically arranged slotted guide 17', 90 rigidly secured to the side of the wagon body, by any suitable means. The supporting rod is provided at its inner end with a depending stop portion 18' and outwardly of and near and spaced from the stop 18' 100 with a laterally extending U-shaped locking portion 19', as shown.

The numeral 20' designates a preferably horizontally arranged locking bracket, attached to the side of the wagon body.

In operation the frame 12 may be swung to the more or less horizontal position, Figure 1, and held in this position by the locking portions 19' of the rods 16' engaging over the lower end walls or the slotted 110 guides 17'. The draft animals of the rear team may be connected short with the frame

12, by any suitable means, and hence will be retained a suitable distance in the rear of the forward wagon body, so that they cannot approach the same too closely, to cause 5 injury to the end gate thereof. When it is desired to unload or dump material from the rear end of the wagon, the frame 12 may be swung upwardly, Figure 2, which is accomplished by moving the locking portions 19' out of engagement with the walls of the slotted guides, and then shifting the frame upwardly, the laterally extending stops 18' serving to limit this outward movement. When the device is not in use, it is 10 lowered to the position in Figure 3, and the upper end of each supporting rod 16' is then preferably passed through the locking bracket 20'. The rod 16' being slightly resilient, its upper end may be bent rearwardly sufficiently, the rod engaging the upper end wall of the slotted bracket 17', so that the stop 18' may clear the locking bracket 20', and pass therethrough and above the same. The rod may now spring 15 forwardly, the stop 18' engaging above and over bracket 20', and the locking portion 19' engaging or being arranged adjacent the outer end of the bracket 20'. The frame 12 is therefore securely held in the lowered 20 position, and the rods 16' held against undue movement and rattling.

It is to be understood that the form of my invention herewith shown and described is to be taken as a preferred example of the 35 same, and that various changes in the shape, size and arrangement of parts may be resorted to without departing from the spirit of my invention or the scope of the subjoined claims.

Having thus described my invention, I claim:

1. A leading device comprising, a frame pivotally connected with the rear portion of a wagon body or the like, said frame being 45 adapted to have the draft animal or ani-

mals of the rear wagon hitched thereto, said frame also being adapted to be shifted to raised and lowered positions, and means to hold the frame in the raised position.

2. A leading device comprising, a frame 50 pivotally connected with the rear portion of a wagon body or the like, said frame being adapted to have the draft animal or animals of the rear team hitched thereto, said frame also being adapted to be shifted to 55 opened and closed positions, supporting means connected with the frame, and means to lock the supporting means to the wagon body.

3. A leading device comprising, a frame 60 pivotally connected with the rear portion of a wagon body or the like, said frame being adapted to have the draft animal or animals of the rear team hitched thereto, said frame also being adapted to be swung to 65 opened and closed positions, diagonal supporting rods pivotally connected with the frame and provided near their free ends with U-shaped locking portions, and slotted brackets secured to the wagon body and receiving the supporting rods.

4. A leading device of the character described, comprising, a frame pivotally connected with a wagon body or the like, and adapted to assume opened and closed positions, supporting rods pivotally connected with the frame and provided near their free ends with U-shaped locking portions and at their free ends with transverse stops, substantially vertical slotted guide brackets secured to the sides of the wagon body and receiving the rods, and substantially horizontal locking brackets secured to the sides of the wagon body to receive the ends of the rods when the frame is in the closed position.

In testimony whereof I affix my signature.

FRANK H. KINSMAN.
